UNITED STATES PATENT OFFICE.

VITO WILLIAM CAVALLUZZI, OF NEW YORK, N. Y.

FOOT REST.

Application filed July 9, 1925. Serial No. 42,395.

My improvements relate to the class of foot supports used in the cleaning of shoes, and for the use of shoe dealers in fitting shoes, etc., and for analogous purposes, my object being the provision of an attachment for such foot rests, adapted to prevent the slipping of the foot on the support; as hereinafter fully set forth,—the invention consisting in the specific construction, combination and arrangement of parts herein described and claimed.

In the accompanying drawings I illustrate a practical embodiment of the essential features of my invention, although I do not limit myself to the identical form and construction of parts and appurtenances herein shown by way of exemplification, since changes may be made in minor details, and equivalent mechanical expedients resorted to with like results, and without departing from the spirit and intent of my invention in this respect.

With this understanding:—

Fig. 1, represents a perspective view of a standard foot rest to which my new tread attachment is applied;

Fig. 2, is a side elevation, on a larger scale, of the foot rest and tread attachment;

Fig. 3, is a top view thereof;

Fig. 4, is a central longitudinal sectional elevation taken upon plane of line 4—4, Fig. 3;

Fig. 5, is a transverse section taken upon plane of line 5—5, Fig. 2;

Fig. 6, is a side elevation of my new tread plate attachment before application of the frictional facing thereto;

Fig. 7, is a bottom view of the attachment plate as shown in Fig. 6;

Fig. 8, is a top view of the frictional facing.

The standard S, or other equivalent support for the foot rest R, may be of any well known or suitable type or configuration, according to conditions and requirements of use, as for shoe cleaning stands, sales foot rests, etc.,—said foot rest R, being formed with the usual heel offset r.

My attachment A, consists essentially of a tread plate T, provided with clamping means for securing it to the foot rest R, and faced with a layer F, of granuliferous material, such as emery cloth, coarse sand paper, or other suitable analogous material, constituting a rough contactual surface for the sole and heel of a shoe or other foot wear.

In the specific form and construction of parts shown in the drawings, the tread plate T, is formed of sheet metal with integral side straps t, t, adapted to straddle and embrace the foot rest R, the ends of said side straps t, t, being perforated for the accommodation of screw bolts b, b, by which the tread plate may be detachably secured to said foot rest R, as indicated more particularly in Figs. 2, 4 and 5, said tread plate T, being also preferably formed with end flanges t', t', fitting over the ends of the foot rest R, as shown in Figs. 2 and 4, of said drawings.

A simple and effective means for securing the facing of granuliferous material F, to the tread plate T, is to form the latter with protuberant clinch-bars t², t², as in Fig. 6, adapted to penetrate said facing material, so that when said bars t², t², are bent over against said facing material F, as indicated more particularly in Figs. 2, 3 and 4, of the drawings, the superposed material F, will be held firm and taut upon and against its metallic base T.

The layer of granuliferous material F, affords a rough frictional contactual surface for the soles and heels of shoes, etc. placed on the foot rest R, and is adapted to prevent slipping thereon; and this function is especially efficacious when children's and ladies' foot wear are concerned. Furthermore, my auxiliary tread plate T, is simple and inexpensive, and being readily attachable and detachable in so far as the foot rest R, is concerned, substitution may be effected when desirable at a minimum of cost and labor.

It is to be understood that by the use herein of the term granuliferous facing material, I mean to include any coarse rough, granular surface adapted to function as and for the purpose stated.

What I claim as my invention and desire to secure by Letters Patent, is:—

1. In combination with a foot rest of the character designated, an attachment therefor, comprising a sheet metal tread plate formed in one piece with side straps and with end flanges for embracing the said foot rest, screw bolts engaging with the said side straps, and a facing of granuliferous material secured to said tread plate, substantially in the manner and for the purpose set forth.

2. In combination with a foot rest of the

character designated, an attachment therefor, comprising a sheet metal tread plate formed on its upper side with clinch-barbs for retaining a facing of granuliferous material and with side straps and end flanges for embracing the said foot rest, screw bolts engaging with the said side straps, and a facing of granuliferous material, substantially in the manner and for the purpose set forth.

3. As an improved article of manufacture, a foot rest attachment comprising a tread

plate of sheet metal with integral side strips to straddle and embrace the foot rest and with flanges to engage under the ends of the 15 foot rest, said tread plate being formed with protuberant clinch barbs, and a facing material placed upon said tread plate and having said clinch barbs passed therethrough and bent down upon said facing, and means 20 cooperating with said side strips to hold the tread plate flat against the upper face of the foot rest.

VITO WILLIAM CAVALLUZZI.
